Company, Rochester, N. Y., a corporation of
New York

Application November 25, 1933, Serial No. 699,776

10 Claims. (Cl. 92—43)

This invention relates to paper making machines, and particularly to the type of paper making machines wherein an endless making wire travels through a fixed path about a cylinder at one end, the cylinder being immersed in a flow box.

It is a well-known fact that in order to lay fibers closely together to produce a fine, strong paper, it is necessary to beat the fibers quite thoroughly reducing them to quite a short length. This reduces the strength of the papers but permits the fibers to be laid closely together.

It is also well known that strong paper requires a much longer fiber, but if longer fibers are used a greater quantity of water must also be used, and this renders it difficult to drain off the water if the fibers are to be closely laid.

One of the objects of our invention is to provide a machine which is capable of making a paper in which long fibers are used with a comparatively great amount of water for making a fine grade of strong paper. Another object of our invention is to provide a machine in which the fibers are laid on the making wire during its passage around the greater part of the periphery of the drum. Another object of our invention is to lay a large number of fibers on the making wire during the time the wire is passing around a portion of the cylinder immersed in the flow box. Another object of our invention is to provide a paper making machine in which the making wire leaves the cylinder in a substantially horizontal direction and in which the level of the stuff is higher than the top of the making wire. Still another object of our invention is to provide a machine in which the wire is well covered with fibers before leaving the drum and to provide a machine which flows a layer of stuff over the fibers already laid on the wire as the wire leaves the drum. Other objects will appear from the following specification, the novel features being particularly pointed out in the claims at the end thereof.

Coming now to the drawings wherein like reference characters denote like parts throughout:

Figure 1 is a part side elevation and part section of a machine constructed in accordance with and embodying a preferred form of our invention.

Figure 2 is a top plan view of the machine shown in Figure 1.

Figure 3 is a cross section on line 3—3 of Figure 1, and

Figure 4 is a fragmentary detail view of a por-

tion of a cylinder with the sealing ring and deckle straps shown in sealing relation.

In accordance with our invention, our paper making machine may consist of a drum 1 around which a making wire 2 passes, this wire passing around a large part of the periphery of drum 1, over a series of guide rollers 3, beneath a top couch roller 4, around a suction couch or plain couch roller 5, and thence toward the drum 1, again passing over an adjustable guide roll 6. The making wire is an endless wire belt of suitable width and mesh.

The drum 1 is carried in a flow box having parallel side walls 7 to which the edges of the drum may be sealed in any suitable manner, such as by gaskets or by deckle straps. As shown in Fig. 4 we prefer to provide a sealing ring 8 on the walls 7 this ring having a flange 8a of complementary shape to the flange 1a of the drum. The deckle straps 9, by lying over the complementary flanges form a moisture tight joint around all of that part of the drum 1 and wire 2 which lies in the flow box.

The drum may turn upon hollow trunnions 9. Towards the bottom of the walls 7 there are preferably provided a pair of outlet pipes 10 and 11 which may be used to control the level of the water in the drum.

The drum is suspended in the flow box which receives the mixed stuff through a pipe 12 from a head box 13. The elevation of the stuff in the head box 13 may be controlled in any suitable manner. It is desirable to maintain the level of the stuff at point where the making wire leaves the cylinder—at 14—at a somewhat higher level than the horizontal reach of the wire 2 leaving the drum.

In order to accomplish this the stuff in the box 13 should be kept at the proper level, and we also provide an adjustable slice 15 which can be moved to permit more or less stuff to flow over the wire as it passes from the drum.

The flow box is provided with a tortuous channel or passage formed by the baffles 16. A valve 17 may be used to assist in regulating the flow of stuff through the flow box.

The arrows A indicate the direction of flow which is arranged so that the stuff will be kept in properly mixed condition as it flows around the drum 1 in the same direction as the drum turns. There is an apron 18 which prevents the stuff from escaping from the flow box at the point where the drum 1 and wire 2 enter the box.

The usual type of deckle straps 9 are employed, these straps passing over a series of guide

rollers 20 and moving in the direction shown by the arrows at the same speed as that of the wire 2. These straps regulate the width of the felted fibers laid on the wire, and seal the wire 5 to the cylinder and the cylinder to the sides of the vat.

It is preferable to provide an adjustable bearing 21 for one of the guide rollers 20 supporting the deckle straps 19 so that these straps may be 10 kept at the desired tension.

As best shown in Figure 3, the slice 15 may be moved in slotted guideways 22 by means of the hand wheel nuts 23 which are threaded on the connecting rods 24 attached to the slice 15. By 15 turning these nuts, the space between the bottom of the slice and the top of the making wire 2 can be nicely adjusted so that the desired amount of stuff may flow out over the fibers already laid on the making wire.

20 The outlet pipes 10 and 11 are provided with suitable controlling valves 20 and 21 so that the level L of the water inside of the drum 1 can be controlled. As the stuff flows through the flow box the fibers start to form on the making wire 25 as soon as the wire passes the apron 18. As the drum turns, the layer of fibers gradually becomes thicker on the making wire 2 during the time the wire is passing through the flow box because water drains through the wire and drum and may 30 be drained from the drum by means of the pipes 10 and 11. Thus, by the time the wire reaches the horizontal reach away from the drum, a layer of considerable thickness of moist fibers has been deposited on the wire. This layer may be substantially 35 sufficient for the desired paper.

In order to prevent the washing off of fibers at the point where the wire leaves the top of the pool of stock in the flow box, we have raised the level 40 of the stuff as above described. This is an important point of our invention because we have found that by flowing even a thin layer of stuff over the fibers already laid on the wire, the uneven effect caused by the fibers washing off is entirely overcome.

45 Moreover, there is an additional advantage in forming a paper web in this way. Where long fibers are used and where it is necessary to lay the fibers closely to make a strong, firm sheet of paper, it is necessary to use a large quantity of 50 water. In fact, the reason why long-fiber, closely formed paper is not common is because it is impossible to get a sufficient quantity of water to felt the fibers closely and to remove the water with the known types of paper making machines.

55 With our present machine, however, it will be noted that a large part of the water is drained from the fibers laid on the making wire 2 during the time the wire passes around that part of the drum which is immersed in the flow box, beneath 60 the surface of the stuff. In addition water also passes through the making wire during its run away from the drum in a horizontal direction. Thus the machine may be considered as a two-stage gravity flow wet end machine in that the fibers are laid on the wire on two stages, the first being as the wire passes around the drum and the second stage being as the wire passes from the drum although, of course, these two stages actually form a single continuous operation.

70 As indicated in Figure 1, a large part of the periphery of the drum is used for this purpose. Substantially 270° is employed in the present embodiment of our invention, and even this may be increased slightly by changing the construction of the flow box. While, of course, the fibers laid

on the making wire 2 as it passes around the drum 1 are in a very moist condition, nevertheless, a relatively large number of long fibers can be successively laid on the wire 2 so that by the time the wire leaves the drum, the felt contains a sufficient number of fibers to make a satisfactory paper web.

5 However, an additional layer of stuff is flowed over the fibers beneath the slice 15 as the wire moves horizontally away from the cylinder, because this is effective to prevent any unevenness in the felt and to prevent the washing off of fibers which has been extremely difficult, if not impossible, to overcome with known types of paper making machines.

10 Having thus described our invention, what we claim as new and desire to secure by Letters Patent of the United States is:

1. In a paper making machine, the combination with a flow box, adapted to contain stuff, of 20 a foraminous cylinder mounted in the flow box, an endless making wire extending around a portion of the drum and out over the top thereof, an apron between the making wire carried by the cylinder and the flow box to prevent stuff from 25 leaking through at the place where the making wire carried by the cylinder enters the flow box, means to drain water from the drum whereby fibers may be felted on the wire beneath the surface of the stuff in the flow box, and means for 30 maintaining the level of the stuff at a height sufficient to flow out over the felted fibers on the wire as it leaves the cylinder comprising an adjustable slice movably mounted with respect to the drum.

35 2. In a paper making machine, the combination with a head box adapted to contain a supply of stuff, of a flow box in which a foraminous cylinder is mounted, a making wire passing around said cylinder, means for controlling the 40 water level in the cylinder, and means including the head box for maintaining the level of the stuff in the flow box at such a level that stock is flowed over the cylinder and making wire as it leaves the cylinder whereby washing off of the fibers deposited on the making wire is prevented.

45 3. In a paper making machine, the combination with a head box adapted to contain stuff of a flow box in which a foraminous cylinder is mounted, 50 a making wire passing around said cylinder, means for controlling the water level in the cylinder, and means including the head box and a slice for maintaining the stuff in the flow box at such a level that stock is flowed over the cylinder and making wire as it leaves the cylinder whereby washing off of the fibers deposited on the making wire is prevented.

55 4. In a paper making machine, the combination with a head box adapted to contain stuff of a flow box in which a foraminous cylinder is mounted, 60 a making wire passing around said cylinder, means for controlling the water level in the cylinder, and means including the head box and a movably mounted slice for maintaining the level of the stuff in the flow box at such a level that a 65 controlled flow of stock is flowed over the cylinder and making wire as the making wire leaves the cylinder, whereby washing off of the fibers deposited on the making wire is prevented.

70 5. In a paper making machine, the combination with a head box adapted to contain stuff, of a flow box in which a foraminous cylinder is mounted, a making wire passing around the cylinder and out over the top thereof, means for guiding a portion of the making wire in a direction substan- 75

tially horizontally from the cylinder, means including the head box for maintaining the level of the stuff in the flow box at a level higher than that of the horizontal reach of the making wire 5 whereby washing off of the fibers deposited on the wire is prevented.

6. In a paper making machine, the combination with a flow box adapted to contain stuff, of a foraminous cylinder mounted to turn therein 10 and having the edges thereof sealed against the flow box, a making wire passing around the cylinder and passing substantially horizontally from the top of the cylinder over guide rolls and back to the cylinder, means for felting fibers on the 15 wire beneath the surface of the stuff in the flow box including pipes for draining water from the drum, means for flowing the stuff in the flow box through a channel around at least half of the periphery of the cylinder whereby a substantial felt 20 of fibers may be laid on the wire in the flow box beneath the surface of the stuff and a slice for controlling the flow of stuff over the felted fibers on the making wire as the wire leaves the drum to maintain an even layer of fibers on the making 25 wire.

7. In a paper making machine, the combination with a flow box, of a foraminous cylinder mounted in the flow box adapted to contain stuff, an endless making wire extending around a large 30 part of the periphery of the cylinder and passing to and from the cylinder over guide rollers, and passing from the cylinder over the top thereof in a substantially horizontal direction, means for maintaining the level of the stuff in the flow box 35 at sufficient height to cover the drum and to flow over the making wire leaving the drum, means for withdrawing water from the drum whereby fibers may be felted on the making wire as it passes about the drum beneath the surface of the stuff, the first-mentioned means also controlling 40 the flow of stuff over the horizontal run of the making wire as it leaves the top of the cylinder whereby a thin layer of stuff may be flowed

over the felted fibers carried on the making wire, and wash-off lines on the paper may be prevented.

8. In a paper making machine, the combination with a flow box adapted to contain stuff, of a foraminous cylinder mounted in the flow box, an 5 endless making wire extending around a portion of the drum and passing from the drum in a substantially horizontal run, an apron between the making wire carried by the cylinder and the flow box to prevent stuff from leaking through at the 10 place where the making wire carried by the cylinder enters the flow box, means to drain water from the drum whereby fibers may be felted on the wire beneath the surface of the stuff in the flow box, and means for maintaining the level of 15 the stuff in the flow box at a height sufficient to flow out over the felted fibers on the wire as the wire leaves the top of the drum in a horizontal run, whereby wash-off lines caused by the felted fibers being drawn from the stuff may be pre- 20 vented.

9. The process of making paper which comprises forming a web of paper from stuff upon a suitable carrier passing through a pool of stuff, maintaining said carrier in a substantially horizontal plane for an appreciable interval of time 25 as it passes from the pool of stuff, and flowing over said carrier and web formed thereon additional stuff directly from the pool while said carrier is in said horizontal position, and draining 30 and drying the web thus formed.

10. The process of making paper which comprises gradually and continuously forming a web of paper from fibers accumulating on a suitable 35 carrier beneath the surface of a pool of stuff, passing the carrier from the stuff in a substantially horizontal direction, flowing over the carrier and fibers first laid thereon additional stuff directly from the pool while said carrier is in a substantially horizontal position and draining and drying 40 the fibers thus laid upon the carrier.

GEROULD T. LANE.
